PATTERNING MECHANISM OF FLAT SINGLE BED KNITTING MACHINES

Gustav Huber, Cleator, England, assignor to Kangol Wear Limited, Cleator, England, a company of Great Britain

Application October 24, 1946, Serial No. 705,327
In Great Britain November 6, 1945

3 Claims. (Cl. 66—76)

1

This invention relates to improvements in flat single bed knitting machines of the type used for knitting berets and similarly shaped articles.

In such machines as hitherto constructed the patterning mechanism controlling the needles for the formation of the sections of the article are operated by patterning mechanism in the form of flats mounted on a cylinder which is reciprocated to bring the flats into engagement with the ends of the needles before each traverse of the cam box, the cylinder being rotated to bring each of the flats successively into the operative position. The flats which vary in length according to the pattern desired are in the form of steel strips which are secured by screws around the periphery of the cylinder and when it is desired to vary the pattern the flats have to be removed from the cylinder and replaced which is a relatively long operation. Moreover the number of flats which can be employed is limited by the diameter of the cylinder.

The aforesaid known construction has also the further disadvantage that it is necessary to reciprocate the relatively heavy cylinder to bring the flats into a position to engage the ends of the needles which also complicates the drive to the cylinder.

One of the objects of the present invention is an improvement in the patterning mechanism which will obviate the necessity of reciprocating the cylinder for controlling the needles and a further object is to allow a much greater number of flats to be employed and to be changed more easily and quickly than is the case with the usual patterning mechanism.

According to the present invention the flats do not directly actuate the needles but control an equal number of two armed members each of which is pivotally mounted on a stationary shaft or bar below the rear ends of the needles, the outer ends of the lower arms resting on the flats when there is no space, gap, slot, aperture or the like therein to allow them to pass through and the ends of the upper arm being adapted to engage the ends of the needles when the ends of the lower arms are resting on the flats, the upper arms of the members held by the flats in the position for engaging the needles being operated by a reciprocating or oscillating bar to cause them to push the corresponding needles into their knitting positions.

The invention is illustrated in and will be described with reference to the accompanying drawings. In these drawings:

Fig. 1 is a transverse section showing the pat-

tern cylinder, a two armed member, the reciprocating bar and a needle, three positions of the two armed member, viz. the operative position shown in full lines, the inoperative position shown in broken lines and the "half-needle" position shown in chain dots;

Figs. 2, 3 and 4 are detailed views in section showing the position of the end of a two armed member relative to the flats and cylinder when in the operative position, the inoperative position and the "half-needle" position respectively;

Fig. 5 is a part plane view of the cylinder and flats;

Fig. 6 is an end view partly in section of a modified form of cylinder and pattern controlling means.

A series of needle controlling members B having two arms b^1 and b^2 are pivotally mounted on a stationary shaft or bar A below the rear ends of the knitting needles C, there being a member B for each needle C.

The arms b^1 and b^2 of each of the needle controlling members B are at an angle (preferably about 90°) to each other and extending rearwardly from the central part or hub b which is pivotally mounted on the shaft A. When a member B is in its operative position, i. e. the position shown in full lines in Fig. 1, its upper arm b^1 is inclined rearwardly at a small angle to the vertical.

The face of the outer end of the upper arm b^1 which engages the needle C is formed with a curved recess b^3 , the curvature of which is such that when the member B is oscillated about the shaft A to actuate the needle C, the pressure on the latter will not tend to move it out of its horizontal path.

The outer end of the lower arm b^2 of the member B is at such angle to the arm that it is substantially vertical and when the member is oscillated it will move in a substantially vertical path. The outer ends of the lower arms b^2 of some of the members B are formed with a shoulder b^4 for a purpose which will be hereinafter described.

The pattern mechanism shown in Fig. 1 comprises a series of flats E carried by two endless bands E^1 , one at each edge which pass around a cylinder D and hang downwards therefrom one or both of the bands being provided with registering holes or eyelets spaced at equal distances apart preferably on the longitudinal centre line of the flats, and these holes or eyelets are engaged by registering pins d on the cylinder D as the latter is rotated.

The cylinder D is carried on an intermittently rotated shaft D¹ below the outer ends of the lower arms B² of the member B. As shown in Fig. 1 the cylinder D is formed on its periphery with a series of flat surfaces, each flat surface being equal to the width of a flat E and being divided by a longitudinal slot or groove d¹ extending from end to end of the cylinder.

The ends of the lower arms b² of the member B normally rest on the flats E as shown in Fig. 2 and when in this position the ends of the upper arms b¹ are in the operative position as shown in full lines in Fig. 1.

Elongated apertures e are formed in the flats E, there being an aperture e for each needle C which it is desired should be inoperative so that when the end of the lower member b² of the corresponding member B is opposite an aperture e the end will fall through the aperture into the slot d¹ in the cylinder as shown in Fig. 3 and the member B will move into the position shown in dotted lines in Fig. 1. If desired the movement of the members B may be assisted by a light spring such as the spring a.

The flats E are preferably formed of a suitable synthetic resin, cardboard, paper or the like, although they may be of metal if desired.

The cylinder D is rotatably mounted in fixed bearings and is rotated therein in a series of intermittent movements from the driving shaft of the machine, each angular movement bringing a successive flat E into engagement with the ends of the lower arms b² of the members B.

Instead of a series of flats E carried between endless bands E¹ as shown in Fig. 5 members B may be controlled by an endless band E² of the necessary width and of a material which is sufficiently flexible to pass round the grooved cylinder D, the patterning apertures e being formed at the required distance apart in the endless band E².

The ends b² of the members B may be lifted out of the apertures e and slots d during the periodic rotation of the cylinder D by suitably shaping the ends or they may be lifted out by positive means such as the bar or rod F which is raised each time the cylinder rotates by suitable mechanism from the driving shaft.

As has been hereinbefore described the needle operating members B are moved into their operative positions for moving the needles C by the flats E or endless band E² and when they are in such position i. e. the position shown in full lines in Fig. 1 their upper ends lie in the path of the front edge g of a bar G extending across the machine and carried by arms pivoted below the axis of the cylinder shaft D¹. The arms H are given an oscillating movement causing the front edge of the bar G to move the curved portions b³ on upper arms b¹ of all the members B which are in the operative position into engagement with the corresponding needles C and move the latter into the knitting position.

Instead of the bar G being carried by oscillating arms it may be carried in slides and be given a reciprocating movement.

In order that the needle at the end of a group to be moved may be moved for half the normal distance i. e. what is usually termed a "half needle" the lower ends of the arms b² of the members B are formed with shoulders b⁴ as previously described and the apertures e¹ in flats E or the band E² for forming the "half-needles" are of half the length of the apertures e. Thus when the end of a member B coincides with a "half-needle" e¹ it will enter into the cylinder groove

d¹ until restrained from further movement by the shoulder b⁴ engaging the flat as shown in Fig. 4 and in chain dots in Fig. 1. When in this position the upper end of the member B as shown in Fig. 1, is out of the path of the front edge g of the bar G but is in the path of a second edge g¹ behind and below the edge g. The bar G thus moves about half its travel before the curved edge b⁴ of the member B engages the corresponding needle C and consequently the latter will only be moved half its normal travel.

The mechanism for omitting the first, second and third needles for forming the crown at the commencement of each section of the article are in the usual form of three stepped cams on the face of a rotating wheel. These cams operate a horizontally sliding finger which moves a plate slidably mounted on the end of the reciprocating or oscillating bar G which has the effect of shortening the effective length of the bar by distances equal to the width of one, two and three needle actuating members B.

I claim:

1. Controlling mechanism for the knitting needles of a flat bed knitting machine of the type used for knitting berets and similarly shaped articles, said mechanism comprising a series of pivotally mounted two armed levers one end of each lever being normally adjacent to the end of a needle, an intermittently rotated cylinder having a plurality of longitudinal grooves spaced at equal distances apart around its periphery, a series of flats arranged as an endless band passing over the said cylinder, the width of each flat being equal to the pitch of the grooves in the periphery of the cylinder, means for registering the flats over the grooves in the cylinder as each groove is below the opposite ends of the two armed levers to the ends adjacent to the needles, each flat being provided with transverse patterning slots through which the end of each two armed lever corresponding to a needle not to be operated according to the pattern will fall into the groove in the cylinder to remove the other end away from the end of the needle and a bar having a to and fro movement which engages the two armed levers which have remained stationary through their ends not falling into the groove in the cylinder and causes them to operate the corresponding needles.

2. Controlling mechanism for the knitting needles of a flat bed knitting machine of the type used for knitting berets and similarly shaped articles as in claim 1 wherein some of the slots in the flats are of half the normal length and a shoulder is formed on the end of the two armed lever whereby when the end of a lever coincides with a short slot it will only fall half the normal distance into the groove in the cylinder and consequently the corresponding needle will receive half its normal movement.

3. Controlling mechanism for the knitting needles of a flat bed knitting machine of the type used for knitting berets and similarly shaped articles, comprising a series of pivotally mounted two-armed levers, one for each needle, one end of each lever being normally adjacent to the end of a needle, an intermittently moved endless patterning mechanism carrying a plurality of equal spaced rows of patterning slots at right angles to its direction of movement, the slots in each row corresponding to the needles not to be operated according to the pattern, whereby as each row of slots is positioned below the ends of the two-armed levers opposite to the ends

thereof adjacent to the needles the said opposite ends will fall into the slots to remove the other ends of the levers from the ends of the needles, and a bar having a to and fro movement which engages the levers which have remained stationary through their ends not falling into the slots and causes them to operate the corresponding needles.

GUSTAV HUBER.
